UNITED STATES PATENT OFFICE.

FREDERICK W. HESSMER, OF JERSEY CITY, NEW JERSEY.

APPARATUS FOR PRODUCING THREADED PINS.

Application filed December 22, 1924. Serial No. 757,384.

My invention relates to improvements in thread cutting machines and it particularly relates to a new and improved method of producing threaded pins, the object of the 5 invention being to provide means to cut the thread as perfectly and accurately as possible.

It is also an object of the invention to provide means by which the points of the 10 threads can be made of slightly conical form.

It is a further object of the invention to provide means by which the operation of cutting the thread can be rendered as speedy as possible so as to reduce the cost of the 15 production.

In the accompanying drawings

Fig. 1 is a plan view of the machine illustrating the preferred form embodying my invention,

20 Fig. 2 is a side elevation,

Fig. 3 is a front elevation, and

Fig. 4 is a side view of the arm holding part of the regulating device and Figs. 5 and 5^a are side and top views, respectively 25 of the arm and of the regulating device to give the pins a pointed head.

Fig. 6 is an illustration of one of the threaded articles made according to my new invention.

30 Like numerals refer to like parts in the several figures.

In the drawings 1 denotes a bed plate provided on the supporting frame 2, the plate carrying a frame 3 upon which journals 4 and 5 are secured, shaft 6 being movably arranged in said journals. In about the middle of main shaft 6 there is a lead screw 7 provided adjoining pulley 8; the chuck 9 is provided at the free end of said shaft 6, whereas 40 the other end of same being movably engaged by one of the finger-shaped points of a powerful spring 10. This spring presses against the center point of shaft 6, whereas the other end of spring 10 is similarly held, in the same axis, in the upright arm 11. Upon frame 3 there is provided another journal 12 having a fork-shaped terminal between the arms of which a cylindrical block 13, having an upright arm 14 with a horizontal extension 15 which has as pivot the screws 16 and 17. The arm 15 has an aperture 18 in which by screw 19 a stamp 20 with a thread, answering as to pitch and other measurements screw 7, is secured, the stamp 20 resting directly upon said thread 7. Arm 15 is furthermore at its free end ex-

tended into a hook 21 to hold a weight 22 thereby.

Upon frame 3 there is also mounted a journal 23 to which at its upper end arm 24 is pivoted in such way that the downwardly bent end is movably secured to said journal by means of the screw points 25 as a pivot, while rod 26, which at its other end is movably laid through journal 27, is rigidly secured to arm 24 by means of screw 25 so that it will follow all movements of arm 24.

The free end of arm 24 has the shape of the letter V turned upside down, and is at its utmost end of a fork-shape, between the 70 arms of which a wheel 28 is movably arranged and held in position by means of pin 29. This latter wheel is resting (Fig. 3) upon the highest point of eccentric or cam-wheel 30 secured to auxiliary shaft 31 movably arranged in journals 32 and 33 and operated by pulley 34. At the other end of shaft 31 there is a guide-wheel 35 secured to it, about one half of its face being broken away.

This guide wheel 35 presses against a little pulley 36 movably held by pin 37 within fork 38 of shaft 39 movably arranged within journals 40 and 41. Furthermore there is a standard 42 at the top of which by means of a screw a flat lever 43 is movably secured, said lever 43 having a slit 44 put over the upright pin 45 on shaft 39. At about its middle lever 43 is twisted 90 degrees and is provided with a hook 46 which is engaged 90 by a powerful spring 47 held at its other end by hook 48 attached to bed plate 1. At the end of the vertical part of lever 43 the same has another slit 49 (Fig. 3) through which a rod 50 is passed. This rod 50 is supported by a U-shaped frame 51 having in its upright arms 52 and 53 suitable openings through which the rod 50 is passing, being at the same time supported by same; the frame 51 in its turn is secured to the structure by being rigidly connected to the bent brace 54 held in position by strong screws upon journal 55 (Fig. 3) secured to bed plate 1. Between the upright arms 52 and 53 rod 50 is provided with the two knobs 56 and 57 a certain distance from each other.

It is obvious from the drawings that rod 50 leads to and disappears within the lowest point of box 58 representing a magazine held in an inclined position by the plate 59, having a hole 59^a secured to journal 55; the arm 62 is secured to journal 55 and reaches into

magazine 58 to regulate the feeding of the pins.

In the field in the bed plate between the length sides of frame 3, in which the journals 4 and 5 are put in, there is a block 63 (see Fig. 4) which is provided with a mold adapted to receive a cylindrical body. The lowest point of this mold is on the same level with the lowest point of rod 50 as well as of the lowest point of the inside of box 58. In the arm 24 there is a slot in which a stamp 64 provided with a chasing cutter or thread 65, is secured by screw 66 to said arm 24, screws 67 and 68 preventing said die 65 from slipping towards the sides; there is another recess or hole in said arm 24 close to wheel 28 in which a strong iron rod 69 is movably secured therein to carry a heavy weight 70 at its lower end.

Close to pulley 8 there is on each side of same a hole 71 and 72, respectively, through which a belt may be laid over pulley 8 and pulley 73 on shaft 74, same being actuated by loose and fast pulley 75 and 76, respectively; pulley 34 is actuated by means of pulley 77 indicated on shaft 74.

Finally there is arranged on platform 1 a standard 78 the upper end of which serves as a pivot to a bent arm 79 with a platform 80 at its end located below a set screw 81 in arm 24 and a wheel 82 rotatably arranged within its fork-shaped end, the wheel 82 being in contact with the cam-wheel 83 having a depression 84 upon shaft 31. The surface of platform 80 is preferably parallel to the straight part of the arm 24, or its central axis if of round form, in which set screw 81 is secured.

The shifting of the belt from loose pulley 75 to the fast pulley 76, and vice versa, is not shown as it is not necessary to dwell upon such matters familiar to men who know the art, likewise lubricating devices are not indicated when their provision is a well understood matter.

I am going to describe now the operation of my new invention which is preferably for cutting threads upon round iron or steel pins having one of their ends flattened out so as to be of more or less prismatic shape at this end and being of slightly cone-shaped form with rounded head at the other end, all the pins being of exactly the same length.

Assuming that the machine in the moment it is started to run is standing exactly as seen in Fig. 1, it is obvious from the above that the rod 50 during the continuation of the motion of guide wheel 35 will push the pin at the lowest point of box 58 out of same through the hole 59^a over to and above onto block 63.

Chuck 9 has a recess of rectangular shape so that the prismatic end of the pins will fit in and as soon as rod 50 pushes the pin 65 onto block 63 it is ultimately entering chuck

9 and retained by it while being pressed against said chuck by rod 50. This is effected, as already alluded to above, by means of guide-wheel 35. Part of the face of wheel 35 being broken away, lever 43 is pushed outwardly when the high points of the edge of guide-wheel 35 press against wheel 36 thus pushing shaft 39 with its pin 45 outwardly which movement the lever is forced to follow. The reverse is taking place when spring 47 contracts and presses lever 43 against pin 45 causing shaft 39 with wheel 36 to press against and follow the edge of guide-wheel 35 all over the recessed part. The effect of these forth and back motions is very important because any time lever 43 turns towards the magazine 58 it pushes the rod 50 all through the lowest part of said magazine 58 thereby pushing the pin admitted by regulating arm 62 into the lowest part of said magazine, out of same and through hole 59^a onto block 63 where its prismatic head is caught and held by chuck 9. The pin immediately follows the rotation of shaft 6 and at this moment arm 24 is also lowered until the stamp 64 with the chasing cutter 65 at its lowest end reaches down upon the pin resting during its rotation upon block 63.

As the heavy weight 70 is acting upon arm 24 it is natural that the chasing cutter 65 of stamp 64 will cut a thread into the pin during its rotation. The length and other details of this thread are regulated by two factors, to wit: the lead screw 7 in connection with the die 20 sliding along said thread and the eccentric or edge cam 30 in connection with wheel 28 at the V bent end of arm 24. In Fig. 4 stamp 64 with thread 65 is seen lifted off block 63 as wheel 28 is practically at the highest point of said edge cam 30, but from the form of this latter cam it is obvious that arm 24 will lower in the further course of rotation and that it will cut a thread into the pin as soon as said arm 24 is sufficiently lowered to bring stamp 64 with thread 65 into contact with the pin.

While this cutting action is performed wheel 28 is out of contact with the eccentric cam 30. Owing to the great difference in diameter between pulleys 8 and 34, both being actuated by the same driving shaft 74, the chuck 9, holding the pin on block 63, makes during this cutting action a considerable number of revolutions in the time the wheel 28 is out of contact with eccentric cam 30 whereby a thread almost up to the cone-shaped, somewhat rounded head of the pin is cut. In order to give the pin a uniform thread which reduces in width only closely at the cone-shaped end of the pin a regulator is provided which consists of the pivotally arranged arm 79 with its platform 80 and the wheel 82. The cam 83, being of small diameter and having a depression 84, is rigidly secured on shaft 31

and in operative engagement with the wheel 82 of arm 79. The set screw 81 arranged in arm 24, operatively engages said arm 79 at its platform 80 and thus brings arms 24 and 5 79 in co-operative relation to each other. The diameter of the cam 83 is made of such length as to bring wheel 82 of bent arm 79 into contact with cam 83, on shaft 31, when wheel 28 gets out of contact with cam wheel 10 30 and as in this latter moment arm 24 drops and the thread 65 of stamp 64 begins to cut the thread into the pin rotated on block 63, it stands to reason, as long as said wheel 82 rotates on cam 83 and all 15 points of the periphery of same are equidistant from its center, and furthermore set screw 81 is in contact with the platform 80, that the thread cut into the pin is all along of the greatest uniformity. As, however, 20 the periphery of cam 83 for a part of its circumference is interrupted by a depression 84, naturally the thread 65 may sink slightly deeper and produce a thread of less width at the cone-shaped end of the pin.

25 In addition to these elements and their functions as described, also the set screw 81 serves to regulate the cutting action of the thread 65 for by turning said screw 81 in either direction the depth to which said 30 thread 65 may sink, may be either increased or shortened within limits of a thousandth of an inch and the measurements of the thread in the pin are changed accordingly.

35 During this cutting action shaft 6 moves towards spring 10 because stamp 20 acts on lead screw 7, thereby causing the two finger-shaped ends of spring 10 almost to come together. In this moment the thread of the 40 pin has the desired length and the pin must then be removed to make room for the next one.

The removal of the pin is caused by the effect of four different actions, two of same 45 going on simultaneously. The first of these four actions is the lifting of stamp 64 with the thread 65 off the pin by cam wheel 30, lifting arm 24, and the other simultaneous, similar action is the lifting of arm 15, and thereby also of stamp 20, off lead screw 20, 50 by means of a projection 26^a indicated in dotted lines on shaft 26, said projection pressing arm 15 upwardly in the moment when arm 24 is lifted by cam-wheel 30. These two simultaneous actions allow spring 55 10, of powerful construction, to push shaft 6 back to its original location after edge guidewheel 35 has shortly before pushed lever 43 to the outside thereby taking rod 50 along.

60 The withdrawal of rod 50 is so timed that

there is no longer any pressure on the finished pin so as to allow the finished pin to be thrown out of chuck 9 and block 62 when spring 10 presses shaft 6 back to its original position, the finished pin drops into an inclined guideway 79^a into a receiver (not shown) from where it is taken for further treatment.

It is understood that many changes can be made in the construction of the machine 70 as described and the ascending and descending of the stamp can be arranged in various ways without departing from the principle or spirit of my invention; likewise also the reciprocating of the shaft holding the chuck 75 can be brought about in different ways, but any such change which in its result is the same as that brought about by the present invention will be claimed as coming within the scope of the appended claims. 80

What I claim is:

1. In a thread cutting machine adapted to press a chasing cutter into the goods to be treated, the combination comprising means regulating the depth to which the chasing 85 cutter is to be pressed, said regulating means consisting of a rotary shaft, a cam of large and another cam of smaller diameter arranged on said shaft, a pivotally arranged bent arm holding a chasing cutter and having at its free end a wheel engaging aforesaid cam of large diameter, a set screw arranged in aforesaid arm, and a pivotally arranged bent arm having at its free end a 90 guide-wheel and having a platform co-operatively disposed below and with aforesaid set screw. 95

2. In a thread cutting machine adapted to press a chasing cutter upon the goods to be treated, the combination comprising means regulating the depth to which the chasing cutter is to be pressed, said regulating means consisting of a pivotally arranged and periodically ascending and descending lever arm, having its free end form an inverted V with a fork-shaped terminal, a guide-wheel arranged in said terminal, a set screw arranged in the lever arm, a chasing cutter vertically adjustably arranged in aforesaid lever between its pivot and aforesaid screw, 105 a pivotally arranged bent arm, having a fork-shaped end, co-operatively disposed below and engaging aforesaid set screw, a guide-wheel arranged in the fork-shaped end of said bent arm, and a cam with a curved-in periphery engaging the guide-wheel of said bent arm. 110 115

In testimony whereof, I have signed my name to this specification May 12th, 1923.

FREDERICK W. HESSMER.
